AIRFOIL CONSTRUCTION

George E. Barnhart, Pasadena, Calif.

Application February 16, 1937, Serial No. 126,005

1 Claim. (Cl. 244—42)

This invention relates to airfoil construction for airplanes.

It is a primary object of this invention to produce a control mechanism for actuating flaps and the like in the airfoil structure which is completely enclosed within the wing or airfoil structure. Through the use of an enclosed mechanism of this nature, I provide a structure which does not interfere in any way with the stream 5 line of the airfoil, thereby avoiding the introduction of wind resistance which would otherwise result from mechanism projecting beyond the airfoil surface. Furthermore, by enclosing the mechanism within the wing, I am able to use 10 parts of lighter weight in the control mechanism since the parts are not subjected to wind stresses during the travel of the airplane.

The flaps contemplated by this invention are what may be termed a split trailing edge type 20 in that they are pivotally mounted in the trailing edges of the wings so that the trailing edges of the flaps are substantially coincident with the trailing edges of the wings, the flaps being pivoted along axes which lie a substantial distance ahead 25 of the trailing edges. These flaps, as was pointed out above, will find their most extensive use during landing and taking off in that when they are lowered or swung downwardly from the wing, they increase the head resistance and the lift, and 30 decrease the air speed of the plane.

For most satisfactory operation, I have found 35 that the flaps must be constructed so as to permit their being swung downwardly at an angle in excess of 40° with their normal folded position. It is, therefore, a further object of this invention to produce a control mechanism of the class described which is capable of swinging the flaps 40 downwardly at angles in excess of 40°.

Although the control mechanism contemplated 45 by this invention may be manually operated or adapted for manual operation, I consider it a further object of the invention to produce a control mechanism which operates automatically within certain limits, depending upon the air speed of the airplane or the wind pressure around the airplane which is a function of the air speed. In other words, the automatic feature of my invention contemplates the provision of means 50 which will automatically lower the flaps when the air speed of the plane decreases beyond a predetermined limit or which will automatically raise or fold the flaps when the air speed exceeds a predetermined limit. In other words, in taking off, the air speed is relatively low and the flaps 55 are in a lowered position thereby increasing the

lift which assists in attaining high elevation within a short distance relative to the ground so that a plane built for normally high speeds can be easily maneuvered to obtain ample "clearance" elevation before it passes the boundary of even 5 small landing fields. When the speed of the airplane has reached the predetermined speed limit, mentioned above, the automatic means referred to are effective to withdraw the flaps without any attention whatsoever from the pilot. When the 10 plane is being maneuvered for landing, the pilot will cut off the motor, and when the velocity of the airplane decreases to a predetermined point, the flaps will be automatically lowered, which further reduces the velocity so that the airplane 15 can be landed in safety. This feature is obviously very valuable in planes which are designed and built for extremely high speed.

Since the flap, or flaps, contemplated by this invention, are preferably constructed so as to 20 extend the full length of the wing, I have devised a novel aileron construction which permits a full length flap of this nature, and my invention, therefore, further contemplates such an aileron 25 construction. In this connection, it is a further object of this invention to produce an aileron of the class described which is disposed at an angle other than 90° with the direction of the flight or is substantially normal to the line of air flow 30 across the wing in the tip portion where the aileron is located.

It is a still further object of this invention to produce a control mechanism of the class described which is of simple form and construction; is light in weight; and has a minimum of 35 operating parts.

The details in the construction of a preferred form of my invention, together with other objects attending its production, will be best understood from the following description of the accompanying 40 drawings which are chosen for illustrative purposes only, and in which—

Fig. 1 is a plan view which illustrates, more or less diagrammatically one form of flap construction and flap control mechanism contemplated by this invention;

Fig. 2 shows an airfoil section which may be considered as having been taken in a plane represented by the line 2—2 in Fig. 1;

Fig. 3 is an airfoil section showing a modified 50 form of control mechanism;

Fig. 4 is a sectional view which may be considered as having been taken in a plane represented by the line 4—4 in Fig. 3;

Fig. 4A is a diagrammatic view showing a mod- 55

ified form of pressure operated flap actuating means;

Fig. 5 is a fragmentary airfoil section showing another form of flap operating mechanism;

5 Fig. 6 is a plan section taken in a plane represented by the line 6—6 in Fig. 5;

Fig. 7 is a fragmentary plan section with parts broken away showing part of a fuselage and a wing, and illustrating a preferred form of automatic control contemplated by this invention;

10 Fig. 8 is a wiring diagram showing one manner of controlling the flap actuating mechanism shown in Fig. 7.

More particularly describing the invention as 15 herein illustrated, reference numeral 11 indicates an airplane comprising a fuselage 12, and wings 13 and 13'. The fuselage is equipped with a propeller unit generally indicated by reference numeral 14, and is provided with a cockpit indicated at 15.

20 In the airplane shown in Fig. 1 the wings are equipped with a flap unit shown as comprising a plurality of flaps which I may refer to as an inner flap 16, and intermediate flap 17, and a tip flap 18. By arranging the flap unit in this manner, I may form the inner and outer flaps so that they "wash" or load the air inwardly toward the center of the wing which carries the intermediate flap. However, it is to be understood that a single flap 25 extending the entire length of the wing, may be employed and that such flap may embody the characteristics of any one of the three flaps shown. In other words, I may employ a flap which extends the entire length of the wing 30 wherein the leading edge of the flap converges from a point nearest the fuselage toward the trailing edge of the wing, or the flap may be one in which the leading edge of the flap is parallel with the trailing edge of the wing, or the flap 35 may be one in which the leading edge converges from a point nearest the tip toward the trailing edge of the wing, each of these flaps having the attending advantages for the particular use for which the plane is designed.

40 It is another feature of the flap construction, contemplated by this invention, that the flap is of the split trailing edge type in that it normally cooperates with a substantially fixed portion 20 of the wing to form a stream line airfoil section. 45 In other words, the wing may be considered as having a flap opening 22 disposed at or near the trailing edge and, as shown in Figs. 2 and 3, the flap indicated by reference numeral 18 is pivotally mounted as indicated at 23 along the front 50 or leading edge of the flap opening 22. The flap is of a width such that when it is in a closed or normal flying position its trailing edge engages and closes the trailing edge of the flap opening.

55 The present invention, however, is more particularly concerned with the flap operating mechanism than it is with any specific type of flap, and in Fig. 2 I show one preferred form of flap operating mechanism which comprises a pair of links, or a plurality of pairs of links, indicated 60 at 24 and 25, such links being pivotally connected at 26 to form a hinge.

65 The "free" end of the link 25 is pivotally attached to a brace member or other suitable support in the substantially fixed portion 20, as indicated at 27, and the "free" end of the link 23 is pivotally connected to the flap 18 as indicated at 28. This hinge member, made up of links 24 and 25, is constructed so that when it is in a folded position it is effective to close the flap, and when 70 it is opened it is effective to swing the flap down-

wardly. It is one feature of this mechanism that it is capable of opening the flap to an angle in excess of 40°.

75 Although various means may be employed to actuate the hinge member, I show in Fig. 2, a construction which is simple and easy to operate. In this construction, the flap is urged toward a closed position by means of a tension spring 30 interposed between the hinge member and the fixed portion of the wing, and is adapted to be 10 swung downwardly to an open position by opening the hinge member through the medium of a cable, or other flexible member, 32, which is shown as being attached to the pivot point of the hinge member and extends over pulleys 33 and 33' mounted on suitable rigid elements such as the spars 35 and 35' of the airfoil. This cable extends over other suitable pulleys, not shown, until it is brought to a convenient point in the cockpit where it is attached to a lever member 36. 20

25 In the event a plurality of flaps are used, I may connect each pair of flaps (corresponding flaps in opposite wings) to a separate lever so that they can be independently operated, or I may connect the cable from all of the flaps to one 30 pair of main control cables which in turn are connected to a single lever. I may also dispense with the spring 30 and employ two cables, one leading from each side of the hinge member so that the movement of the lever in one direction is effective to open the hinge, and the movement in the opposite direction is effective to close the same.

35 It was pointed out in the early part of the specification that, in addition to the flap control mechanism, this invention contemplates a novel type of aileron which is the nature of an auxiliary flap. Such an aileron construction may be mounted either on the top surface of the wing or at the bottom surface of the wing, or, a flap 40 may be mounted on both such surfaces. In Fig. 2, this aileron type of flap is shown as being mounted on both such surfaces. The top aileron is indicated by reference numeral 37, and the bottom aileron is indicated by reference numeral 38. 45 These aileron flaps, unlike the flaps 18, are adapted for reception in the recesses of the wing surface, and are shown as being pivoted at their leading edges as indicated at 39 and 40. It is one feature of this type of aileron that it is 50 mounted between the centers of pressure travel in the wing. In other words, the flap is preferably located substantially between the center of pressure location for high speed travel and the center of pressure location for low speed travel. 55

60 It is another feature of the flap 37, that it is disposed or arranged in substantially normal relation to the mean line of air flow across the wing in the particular region where the flap is located. This feature is best illustrated in Fig. 1 but the line of air flow for the region of the aileron is indicated by the reference letter L. It is to be understood, of course, that this arrangement of the aileron may be used in both the top and bottom flaps in the event two flaps are 65 used. For the purpose of illustration, however, the bottom flap in this form of my invention is shown as being arranged in the usual manner where it is normal to the line of travel or parallel to the leading edge of the wing. 70

75 For the purpose of actuating the aileron 37, I show the same as being mounted upon a shaft which is provided with a lever member 42 extending through a suitable slot or opening in the wing to a point within the wing. The free end 75

of this lever member 42 is connected to a pair of cables 43 and 43' which extend over pulleys 44 and 44' and additional pulleys (not shown) to a point in the cockpit where they are attached 5 to an operating lever similar to the operating lever 36. The bottom flap 38 is rigidly associated with a lever member 44 and is urged toward a closed position by means of a tension spring 45 and is adapted to be swung to an open 10 position by means of a cable 46. In this particular arrangement, the aileron flaps are adapted for independent operation, but it is to be understood that they may be interconnected for simultaneous operation by means of a suitable link 15 mechanism or by the cable control system.

In Figs. 3 and 4, wherein the wing structure and the flap are identical with the wing structure and flap in Fig. 2, and are indicated by the same reference numerals distinguished by the 20 prime mark, I show a modified form of flap control mechanism. This control mechanism is shown as comprising a pair of links 50 and 51 pivotally connected at 52 to form a hinge. The free ends of these links are connected, for swinging movement, about two axes to the rigid portion 25 of the wing and the flap 18 as indicated at 53 and 54 respectively. In this particular arrangement, the hinge member is arranged to operate in a plane extending along the length 30 of the wing, and since the hinge must swing as a unit during the pivotal movement thereof which opens and closes the flap, it is necessary to employ the double acting pivot units 53 and 54.

This particular type of hinge construction 35 lends itself especially to use in connection with a hydraulic actuating mechanism, and although a cable or other type of actuating mechanism may be employed with this hinge, or a hydraulic mechanism may be employed with the type of 40 hinge shown in Fig. 2, I show in Figs. 3 and 4 a hydraulic cylinder or a plurality of such cylinders indicated generally by reference numeral 55, the cylinder 55 containing a piston 56 which carries a piston rod 57. The outer, or free end, 45 of the piston rod is pivotally attached to a link 58 which in turn is connected to the pivot point 52 of the hinge unit.

The piston is adapted to be reciprocated in the cylinder 55 for actuating the flap by means of 50 what I may term a power cylinder 60 which contains a piston 61 having a piston rod 62 adapted for actuation by a lever member 63. The lever member 63 is of course situated convenient to the pilot in the cockpit.

The power cylinder 60 is connected to the flap 55 actuating cylinder 55 through the medium of a pressure fluid conduit 64, and the whole system is filled with a suitable pressure fluid such as oil, glycerin, or the like. In this particular form of my invention, I depend upon the suction, created in 60 the power cylinder by the retraction of the power piston, to withdraw the piston 56 and retract the flaps. It will be understood, however, that I may employ fluid lines to connect both ends of 65 the respective cylinders so that there is positive pressure on the piston 56 for both the opening and closing operation, also that a Sylphon bellows or a diaphragm system may be employed as an operating means. A bellows system is shown in 70 Fig. 4A where the bellows, indicated at 55' and 60' are interconnected by a fluid conduit 64'. The bellows 60' is actuated by a lever 63' and the bellows 55' actuates the flap operating links 50' and 51'.

In Fig. 5 I show another modified form of my

invention in which the flap, indicated by reference numeral 18a, is rigidly mounted upon a shaft 67 which is rotatably supported by bearing brackets 68 shown as being mounted on a spar 35a, the shaft 67 extending substantially parallel to the axis of the wing. The inner end portion of the shaft 67 is provided with a lever member 67' which is connected through the medium of a link, or system of links, 69, with a manually actuated lever 70. This system provides a simple and compact flap operating mechanism.

It was pointed out in the forepart of the specification as one object of this invention to provide a flap control mechanism which was automatically effective to open and close the flaps, depending upon the air speed of the airplane. Such a system is illustrated in Figs. 7 and 8 wherein the flap indicated by reference numeral 70 is of the general construction referred to above, and is shown as being provided with hinged members indicated at 71 and 71' for opening and closing the flap in the manner described in connection with Fig. 2.

These hinge members are connected at their pivot points to oppositely extending cables 73, 73' 25 associated with suitable supporting pulleys 74. The cables 73 are shown as being united at 75 where they continue as a single cable which extends over a pulley 76 and is connected to a rack 77. The other end of the rack 77 is connected to a 30 similar extension of the cables 73'.

The rack 77 is engaged by a pinion 78 which is keyed to a shaft of a suitable power device, such as a reversible electric motor 79. The current to the motor is adapted to be reversed by means of a 35 vane or other suitable wind pressure mechanism indicated at 80. In this particular form the vane 80 is shown as being pivoted in the side of the fuselage and is pressed outwardly by means of a compression spring 81.

The vane 80 is associated with, or as shown, is attached to a reversing switch generally indicated by reference numeral 82 whereby the current through the motor is reversed for effecting opposed movements of the rack 77. In operation 40 the spring 81 is of a strength such that it will resist a predetermined wind pressure against the vane, such pressure resulting from the movement of the plane so that when the plane is standing or moving at slow speeds, the vane 80 is pressed 45 outwardly, closing a circuit through the motor which drives the rack in the direction of the arrow "A" to swing the flap downwardly, such movement of the rack being continued until the end of the rack engages a circuit opening switch 50 indicated at 84. When the plane attains a predetermined speed, the wind pressure against the vane 80 is sufficient to press the vane inwardly 55 against the action of the compression spring thereby closing a reverse circuit through which 60 the motor then drives the rack in the direction of the arrow "B" thereby closing the flap.

In Fig. 8, I show a wiring diagram for one type of circuit which may be used in conjunction with a device of this character. From this 65 diagram it will be noted that the motor 79, when set for automatic operation, is adapted to be driven from a battery 85 through a circuit control switch 86 and a circuit containing the vane actuated control switch 82.

The device is also equipped for manual operation, such operation being effected by throwing the switch 86 to connect the battery with another circuit C'. This last mentioned circuit contains a manually operated reversing switch 82' which 70 75

is actuated by means of a lever member 80' instead of the vane 80. The lever member 80' will be situated in the cockpit of the fuselage and its actuation will have the same result upon the 5 flaps as the vane actuated switch 82.

Having thus described my invention I claim:

An airplane, a fuselage, an operator's station, and a pair of wings each having a substantially fixed portion, a flap mounted on each wing for 10 downward swinging movement away from said fixed portion, a plurality of fluid pressure devices

for each flap for swinging the same downwardly, said fluid pressure devices being disposed along each wing adjacent its respective flap and operatively connected to the flap, manually operable means adjacent said operator's station, means for compressing fluid operable by said manual means and means for connecting said last named means to the fluid pressure devices along the wings for actuating the latter.
